US00D790455S

(12) **United States Design Patent** (10) Patent No.: **US D790,455 S**
(45) Date of Patent: ** *Jun. 27, 2017

(54) **CHARGING UNIT**

- (71) Applicant: **Philip Morris Products S.A.**,
Neuchatel (CH)
- (72) Inventors: **Rory McGarry**, Monkstown (IE);
George Barrett, Dublin (IE); **Florent**
Cuchet, Blackrock (IE); **Cathal**
Loughnane, Gorey (IE)
- (73) Assignee: **PHILIP MORRIS PRODUCTS S.A.**,
Neuchatel (CH)
- (*) Notice: This patent is subject to a terminal disclaimer.
- (**) Term: **14 Years**
- (21) Appl. No.: **29/522,206**
- (22) Filed: **Mar. 27, 2015**

CLAIM

The ornamental design for a charging unit, as shown and described.

DESCRIPTION

FIG. 1 is a perspective view of the front, top, and right side of a charging unit, in a closed position, according to our new design;

FIG. 2 is a right side elevational view thereof;

FIG. 3 is a left side elevational view thereof;

FIG. 4 is a rear elevational view thereof;

FIG. 5 is a front elevational view thereof;

FIG. 6 is a top plan view thereof;

FIG. 7 is a bottom plan view thereof;

FIG. 8 is a perspective view of the front, top, and right side of the charging unit, in an open position, according to our new design;

FIG. 9 is a right side elevational view thereof;

FIG. 10 is a left side elevational view thereof;

FIG. 11 is a rear elevational view thereof;

FIG. 12 is a front elevational view thereof;

FIG. 13 is a top plan view thereof; and,

FIG. 14 is a bottom plan view thereof.

The broken lines in the figures represent portions of the article which form no part of the claim.
